UNITED STATES PATENT OFFICE

JOSEPH ROBELLARD, OF NEW YORK MILLS, NEW YORK, ASSIGNOR TO DRAPER CORPORATION, OF HOPEDALE, MASSACHUSETTS, A CORPORATION OF MAINE

LET-BACK MECHANISM FOR LOOMS

Application filed July 13, 1929. Serial No. 378,069.

This invention relates to a cloth roll take-up mechanism for looms and particularly to the mechanism for controlling the let-back of the take-up mechanism. When the take-up mechanism is positively driven, a means usually including a pawl and ratchet mechanism, is employed particularly for limiting the let-back of the take-up mechanism and therefore of the cloth when the drive is released. But when the take-up is to be turned back by hand, or when the cloth roll is to be unwound, it is necessary to render this mechanism for controlling and limiting the let-back inactive. The principal object of the present invention is to provide means for automatically rendering this mechanism active when the drive of the take-up mechanism is renewed.

In a construction commonly employed for controlling and limiting let-back, there is a 20 detent or let-back pawl which is moved manually into an inactive position by the operator when it is desired to turn the take-up mechanism backward or unwind the cloth roll and frequently the operator neglects to restore this pawl to active position when the take-up 25 is started, thus preventing the proper functioning of the take-up mechanism. The more particular object of the present invention is to provide a simple and effective means for automatically restoring this pawl to active position when the drive of the take-up mechanism is resumed.

These and other objects and features of the invention will appear more fully from the 30 accompanying description and drawings and will be particularly pointed out in the claims.

The drawings illustrate so much of a positively driven cloth roll take-up mechanism of a generally familiar type as is necessary to a 40 disclosure of a preferred form of the present invention.

Fig. 1 is a front elevation of the left-hand portion of a loom with a preferred form of the present invention embodied therein.

Fig. 2 is a detail chiefly in side elevation

looking toward the left of a portion of the mechanism shown in Fig. 1.

As the general construction and operation of a cloth roll take-up mechanism for looms of the type illustrated is well known and familiar to those skilled in the art, it will only be necessary to describe in detail those parts immediately concerned with a preferred embodiment of the present invention.

A portion of the left-hand side frame 1, a lower girder 2, a bracket 3 secured to the loom frame, an intermediate vertical strut member 4, and a bracket 5 secured to the strut 4 all may be of the usual type. The usual take-up roll and the cloth roll driven therefrom are not shown. The take-up roll is driven from a pinion 6 through a train of gearing 7 of the usual type. The pinion 6 is integral with a ratchet wheel 8 and these two elements are journalled on a shaft 9 which in turn is journalled at one end in the bracket 5 and at the other end in a long bearing 10 forming part of the bracket 3. The shaft 9, when the loom is running, is continuously and positively driven by any suitable means such as the positively driven shaft 11 extending transversely thereto and connected therewith by a worm and worm wheel drive.

A suitable clutch member 12 is keyed to the shaft 9 and operated by the lever 13 to clutch the pinion 6 and ratchet wheel 8 to the shaft. Whenever the lever 13 is moved to unclutching position, as under the control of the weft replenishing mechanism, or otherwise, let-back takes place due to the tension of the cloth and the amount of this let-back must be controlled. For that purpose there is commonly provided a let-back or detent pawl cooperating with the ratchet wheel 8. This pawl 14 is shown as secured to a shaft 15 pivoted in a pawl carrier shown as a bell crank lever journalled on the shaft 9, the longer arm of the lever 16 carrying the shaft 15 and the shorter arm being extended forward and formed into a weight 17. Thus the action

of gravity tends to keep the let-back pawl 14 in engagement with the ratchet wheel 8. During actuation of the take-up the pawl 14 rides idly over the teeth of the ratchet wheel 8, but when let-back takes place and the ratchet wheel 8 rotates in reverse direction, the pawl 14 is held by the ratchet wheel and the pawl carrier swings rearward or clockwise. The forward position of the let-back pawl 14 is determined by a stud 18 projecting from the pawl carrier 16 riding in an arcuate slot 19 in a portion of the bracket 5 by engagement of the stud with a cotter pin 20 adjustably positioned in the bracket. When let-back takes place, as when the clutch 12 is disconnected, the amount of let-back is determined by the distance from this cotter pin 20 to the rear end of the arcuate slot 19.

All of the foregoing construction is well known and familiar and for a more detailed illustration and description thereof reference may be had to the patent to La Chapelle, No. 1,647,234, November 1, 1927.

When let-back has taken place, it will be seen that the driving train of gearing 6 and 7 extending to the take-up roll is locked against reverse rotation by the let-back pawl 14. It is frequently desirable to render the let-back limiting means inactive by the release of the let-back pawl so as to enable the take-up roll to be reversely rotated and particularly to enable the cloth to be unwound. In order to do this, the operator swings the let-back pawl 14 about its fulcrum 15 over backward and leaves it in an idle or inactive position, while manipulating the take-up and cloth roll. But when the drive of the take-up mechanism is resumed, the let-back pawl is frequently left in this inactive position and when the loom runs under these circumstances a defect in the weave occurs. In the present invention means are provided for automatically restoring the let-back pawl to active position when the loom starts or the drive of the take-up mechanism is resumed.

As a simple and preferred means for securing this result the shaft 9 is provided with a circumferential series of radial projections which conveniently take the form of the teeth 21 of a second ratchet wheel 22 secured to the shaft 9. A holding pawl 23 is pivoted to the let-back pawl 14 as by being pivotally mounted at 24 in an arm 25 secured to the shaft 15 of the let-back pawl and this holding pawl is of such length that under normal conditions it hangs down in front of the ratchet wheel 22. When it is desired to render the let-back pawl inoperative, the operator takes hold of the holding pawl 23 and raises it until the lower end is seated on one of the teeth or projections 21, thus holding the let-back pawl 14 elevated and out of cooperation with the ratchet wheel 8, as shown in Fig. 2.

When now the drive is resumed and the shaft 9 rotates, the tooth or projection upon

which the holding pawl 23 is seated moves with the shaft, allowing the holding pawl to drop and the let-back pawl 14 to swing into cooperation with the ratchet wheel 8. Thus it is impossible for the let-back pawl 14 to remain out of cooperation with the ratchet wheel 8 when the loom is running or the shaft 9 is rotating. The let-back pawl is automatically rendered active upon the operation of the loom.

There is thus provided a simple and effective means manually operated to render the let-back limiting means inactive and automatically operated upon operation of the take-up drive to render this let-back limiting means active.

Having thus described the invention, what is claimed as new, and desired to be secured by Letters Patent, is:

1. In a loom, positively driven cloth roll take-up mechanism, means for limiting let-back when the drive is released, manually operated means for rendering the let-back limiting means inactive, and means acting upon operation of the drive automatically to render the let-back limiting means active.

2. In a positively driven cloth roll take-up mechanism for looms, a let-back pawl and ratchet mechanism acting to limit let-back to a predetermined amount when the drive is released, means manually movable into a position to render the let-back pawl inactive, and means acting upon the operation of the take-up mechanism to remove said manual means from the said position and to render the let-back pawl active.

3. In a cloth roll take-up mechanism for looms, a shaft, means for rotating the shaft, a ratchet wheel journaled on the shaft and driving connections therefrom for the take-up, means for clutching the ratchet wheel to the shaft, a pawl carrier journaled on the shaft, a let-back pawl pivoted to the carrier and cooperating with the ratchet wheel, means for limiting the movement of the pawl carrier and thereby the amount of let-back upon reverse rotation of the ratchet wheel, a circumferential series of radial projections on the shaft, and a holding pawl pivoted to and depending from the let-back pawl and acting when its free end is seated on one of said projections to hold the let-back pawl out of cooperation with the ratchet wheel and thus permit any desired degree of let-back, the said holding pawl being swung out of engagement with the said projection by the rotation of the shaft when effecting take-up thus to insure return of the let-back pawl to cooperation with the ratchet wheel.

4. A loom comprising a cloth roll take-up mechanism, actuating means therefor including a driven shaft, two ratchet wheels on the shaft, a let-back pawl cooperating with one ratchet wheel to determine the amount of let-back, and a holding pawl manually movable

into engagement with the other ratchet wheel to hold the let-back pawl out of cooperation with the first ratchet wheel and thus permit any desired degree of let-back and automatically moved out of engagement with the second ratchet wheel by the rotation of the shaft thus to insure cooperation of the let-back pawl with the first ratchet wheel upon actuation of the take-up mechanism.

10 In testimony whereof, I have signed my name to this specification.

JOSEPH ROBELLARD.
